RADIO TELEGRAPH RECEIVING SYSTEM

Reynold S. Chapin, Flushing, N. Y., assignor to
Press Wireless, Inc., New York, N. Y., a corpora-
tion of Delaware

Application September 7, 1946, Serial No. 695,530

5 Claims. (CL 250—8)

1

This invention relates to radio telegraph systems and more especially to such systems wherein the telegraph information is represented by keyed "off" and "on" signals.

In present day radio telegraphy, there are two generally used methods of transmission, one identified as make and break, and the other as frequency shift. In the make and break system, the radio carrier is keyed-on for one signal condition, e. g., mark, and is keyed-off to represent space. In the frequency shift system, the radio carrier is continuously transmitted but the frequency is shifted to one value representing mark and another value representing space. One of the advantages of the frequency shift method is an increase in the signal-to-noise ratio as compared with the "off" and "on" system.

Accordingly, it is a principal object of this invention to provide an off and on radio telegraph system having certain of the advantages of the carrier frequency shift system, and in particular the advantage of high signal-to-noise ratio.

A feature of the invention relates to a radio receiving arrangement for receiving telegraph signals of the off and on carrier type, having means to increase the ratio of signal-to-noise by automatically and artificially inserting a carrier at the receiver when no carrier is being received from the transmitter, as for example during the reception of a space signal.

A further feature relates to a novel arrangement for selectively and artificially supplying a local carrier to a radio receiver which normally depends for its signal reproduction on the receipt of a carrier from a distant transmitter.

A still further feature relates to the novel organization, arrangement and relative interconnection of parts which cooperate to provide an improved radio telegraph receiving system.

Inasmuch as the various components of a radio telegraph and receiving system are, in themselves, well-known, the invention will be illustrated in block diagrammatic form. Only those parts of such a system as are necessary to an understanding of the invention and one method of carrying it into practice, are shown. The drawing shows any well-known suitable form of radio transmitter 10 of the well-known carrier off and on type, comprising a carrier frequency generator 11 which can be keyed on and off by the telegraph keyer device 12. The keyed carrier is picked up by any suitable antenna 13, and is applied to two radio receivers 14, 15, each of which may be, although not necessarily, of the superheterodyne type. Each receiver may comprise a radio frequency amplifier stage, a fre-

quency mixer or converter stage which is supplied with local high frequency heterodyne oscillations from the usual source 16, 17; an intermediate frequency amplifier stage, and a detector stage.

The receiver 14 is the main receiver whose output controls the signal responder device 18. Preferably, the detector stage of receiver 14 is supplied with local audio frequency beat oscillations from source 19, and the resultant beat note is passed through a suitable band-pass filter 20. The receiver 15 is an auxiliary receiver and is employed for the purpose of supplying the intermediate frequency stage of receiver 14 with an intermediate frequency carrier when no radio frequency carrier is being applied via antenna 13 to the input of receiver 14. For purposes of explanation, it will be assumed that when a mark signal is being transmitted by the transmitter 10 a radio frequency carrier is picked up by the antenna 13, and when a space signal is being transmitted, no carrier is picked up by the said antenna. Connected to the intermediate frequency stage of receiver 14 is a local intermediate frequency oscillator 21 which normally generates a frequency within the pass-band of the intermediate frequency circuits of receiver 14. The arrangement is such that when no radio carrier is being received by the antenna 13, the oscillator 21 is effective to apply or inject the local intermediate frequency into the intermediate frequency stage of the receiver 14. On the other hand, when a radio carrier signal is being received by antenna 13, the arrangement is such that the oscillator 21 is controlled so that it does not apply any local intermediate frequency carrier to the intermediate frequency stage of receiver 14 within the pass-band of the said stage. It has been found that when the receiver 14 does not receive radio carrier from the antenna 13, and in the absence of oscillator 21, considerable noise is present in the output of the receiver. On the other hand, by injecting the intermediate frequency oscillations artificially from the oscillator 21 as above described, this noise content in the output of the receiver 14 is greatly reduced if not entirely suppressed.

Assume for purposes of explanation that a mark signal is being transmitted. Under these conditions, a D. C. signal appears at the output of receiver 15 which is applied through a low-pass filter 22, in order to increase the ratio of signal-to-noise. This D. C. signal is applied to a reactance tube or reactance modulator 23 of any well-known type, the output of which is coupled to the oscillator 21, so that when a signal is passed

by filter 22 as above described, the oscillator 21 is effectively disabled or at least its frequency is changed to one which is far removed from the pass-band of the intermediate frequency section of receiver 14. For a detailed description of a suitable reactance modulator for controlling the oscillator 21, reference may be had to Radio Engineers' Handbook, by F. E. Terman, first edition, page 654 and 655, published by McGraw-Hill Book Company, Inc., New York, New York.

On the other hand, when no radio frequency carrier is being received corresponding for example to a space signal, no D. C. signal appears at the output of receiver 15. Under these conditions, the reactance tube 23 causes the oscillator 21 to generate a sustained intermediate frequency carrier which is within the pass-band of the intermediate frequency stage of receiver 14. Preferably, although not necessarily, the injected frequency from oscillator 21 is slightly different from the normal intermediate frequency of the receiver 14, which normal intermediate frequency is produced at the output of the mixer stage of receiver 14 by heterodyning the received carrier with the local oscillator 17. However the injected frequency is within the normal pass-band of this intermediate frequency stage. Thus, when the injected intermediate frequency signal is detected and heterodyned with the signal from the local beat frequency oscillator 19, there is produced an audio frequency in the output of the receiver 14 which is slightly different from the normal beat frequency at the output of receiver 14 when a radio frequency mark signal is applied to the input of that receiver. When a radio frequency mark signal is being received, the receiver 14 functions in the normal way to produce at its output an audio frequency beat note determined by the detected signal and the beat frequency oscillator 19. Since the oscillator 19 is continuously operating, the output of the receiver 14 for a received radio frequency mark signal will be an audio frequency tone of a specific frequency, which is different from the tone which is created when no radio frequency carrier is being received, but which results from the injected local carrier.

Preferably, the low-pass filter 22 is adjustable to correlate it with the keying speed of the received signals so as to increase a ratio of signal-to-noise. Likewise, if desired, the sensitivity of the reactance tube 23 and the oscillator 21 can be adjusted to correlate them with the keying speeds in the received signals so as further to increase the ratio of signal-to-noise.

While one particular embodiment has been disclosed, it will be understood that various changes and modifications may be made therein without departing from the spirit and scope of the invention.

What is claimed is:

1. A receiving arrangement for radio telegraph signals of the carrier "on" and "off" type, comprising a main radio receiver whose output controls a telegraph signal responder, an auxiliary radio receiver, means to apply received telegraph signals to the inputs of both receivers, a local carrier oscillator connected to said main receiver to supply carrier artificially thereto when the radio telegraph carrier is in "off" condition, and means controlled by the detected output of the auxiliary receiver for rendering said local carrier oscillator effective on the main receiver.
2. A receiving arrangement for "on" and "off" radio telegraph signals, comprising a main radio

receiver whose detected output controls a telegraph signal responder, an auxiliary radio receiver for producing at its output a control signal when the radio carrier is keyed-on, a local injection oscillator for the main receiver, means responsive to the presence of said control signal to render said local oscillator ineffective to inject carrier into said main receiver so as to affect said signal responder, the last-mentioned means being effective in the absence of said controlled signal to render said local oscillator effective to inject carrier into said main receiver to increase the ratio of signal-to-noise when the radio carrier is keyed-off.

3. A receiving arrangement according to claim 2 in which said main receiver is continuously supplied with beat frequency oscillations to produce in the output of said main receiver two different audio frequency beats, one corresponding to reception of a keyed-on radio telegraph signal and the other corresponding to the keyed-off telegraph signal.

4. A receiving arrangement for "on" and "off" radio telegraph signals, comprising a main radio receiver whose detected output controls a telegraph signal responder, an auxiliary radio receiver, said main receiver being the type having an intermediate frequency carrier stage; a local intermediate frequency carrier generator, and means controlled by the detected output of said auxiliary receiver for rendering said intermediate frequency carrier generator effective to inject local intermediate carrier frequency into said intermediate frequency stage within the pass-band of said stage, the last-mentioned means being responsive to the reception of radio telegraph carrier to render said intermediate frequency carrier generator ineffective to inject intermediate frequency carrier into said main receiver within the pass-band of the said intermediate frequency carrier stage.

5. A receiving arrangement for a telegraph receiving system comprising a main signal receiving channel, an auxiliary signal receiving channel, a local carrier oscillator for artificially injecting a carrier frequency into the main receiving channel when the received carrier is keyed off, a reactance modulator device for controlling the frequency of said local oscillator said reactance modulator being controlled to the detected output of said auxiliary receiver, said main receiver being of the superheterodyne type having an intermediate frequency stage and said local oscillator being arranged to generate a carrier frequency which is within the pass-band of said intermediate frequency stage but is different from the normal intermediate frequency of said main receiver when receiving keyed-on telegraph radio signals, and a beat frequency oscillator is connected to the detector stage of said main receiver to produce two different audio frequency signals corresponding respectively to the reception of a keyed-on and keyed-off radio telegraph signal.
